UNITED STATES PATENT OFFICE.

ALBIN R. FALK, OF MOLINE, ILLINOIS.

AIR-GUN.

1,310,745.

Specification of Letters Patent. Patented July 22, 1919.

Application filed February 15, 1919. Serial No. 277,163.

To all whom it may concern:

Be it known that I, ALBIN R. FALK, a citizen of the United States, residing at Moline, in the county of Rock Island 5 and State of Illinois, have invented certain new and useful Improvements in Air-Guns, of which the following is a specification.

This invention relates to air guns or pistols, and belongs to that class of weapons 10 designed to propel projectiles by means of compressed air, and containing an air compression chamber in which a plunger is drawn by hand in one direction against the force of a spring until caught and held by 15 a trigger device whereby the plunger may be released at will to compress the air.

In this invention the object is to produce an air gun of the class stated, having the compression chamber and the barrel and bore 20 of the gun arranged parallel with each other, the bore and chamber having openings in the same plane which are suitably connected by means of a pivotal breech block, in one position of which the opening into the bore 25 is uncovered for the introduction of the projectile. The special construction and arrangement of the various parts is likewise an object of this invention, as it is believed that such arrangement results in a particu- 30 larly compact, easily understood and operated device, not liable to get out of order and especially cheap to manufacturers.

The accompanying drawings illustrate the special construction and arrangement of 35 the parts of this invention, and Figure 1 represents a rear view showing the peculiar form and disposition of the breech block pivotally carried upon the breech of the piece. Fig. 2 is a vertical section length- 40 wise of the air chamber and barrel of the gun, taken upon the indirect broken line 2-2 of Fig. 1 and showing all parts assem- bled. Fig. 3 is the breech block face.

Throughout the drawings and description 45 the same letter is employed to refer to the same part.

Considering the drawings, which set forth this invention in the form of a pistol, A is the body and a the handle or grip. The 50 body comprises two parallel features, one being the air compression chamber B, and the other and upper portion being the barrel b having the usual bore for directing the projectile. The compression chamber is 55 closed at the outer end by the screw cap C, and the mouth of the bore of the barrel is

usually screw-threaded as at c in practice in order that an extension of the barrel may be attached if desired at any time.

The trigger D acts upon a slide d against the force of a spring E, and the upper wedge-shaped end e of the slide is arranged to catch the edge of a plunger F in the compression chamber, when the plunger is drawn outwardly by the rod f against the 65 force of the coil spring G, by the hand grasping the external eye or finger piece g.

When the plunger is released the air is forced out through the discharge port H which opens into the compression chamber 70 B. From the discharge port the air passes into the groove h in the face of the breech block J. The groove is formed with closed ends, as best shown in Fig. 3, and it is constructed to connect the discharge port H of 75 the compression chamber, and the rear opening or end of the bore of the barrel. The breech block J is pivotally supported and clamped upon the end of the body A by the thumbscrew j, which passes through the 80 block to one side of the groove h. It will be observed that the mouths of the discharge port H and of the rear end of the barrel b lie the same plane, which is the plane of the rear of the body A, and against 85 which the face of the breech block rests. In Fig. 1 is shown the spring K on top of the barrel and the pin k beneath the end of the spring and extending into the barrel in the path of the projectile L, the purpose 90 of the spring pin being to prevent the projectile from falling out of the bore if the muzzle of the pistol is lowered.

In operation, the thumbscrew j and the top of the breech block are turned to the 95 right, which uncovers the open end of the bore of the barrel for the introduction of the projectile L. The block and thumbscrew are then turned back which clamps the block in place with the groove h connecting the discharge port H and the bore of the barrel. If the plunger is now operated the compressed air will rush into the bore by way of the breech block and drive the projectile out of the bore with great 105 force and accuracy.

Having now described this invention, and explained the mode of its operation, what I claim is:

1. In an air gun, the combination with a 110 compression chamber and a barrel having rear openings in the same plane, of a breech

block pivotally supported and movable transversely upon the rear end of said barrel and compression chamber, and the said block having a groove arranged to connect said openings of the barrel and chamber.

2. In an air gun, the combination with a compression chamber and a barrel having openings in the same plane, of a breech

block pivotally supported and movable transversely upon the rear ends of said barrel and compression chamber, a thumbscrew for clamping said block in place, and the said block having a groove arranged to connect said openings of the barrel and chamber.

In testimony whereof I affix my signature. 15

ALBIN R. FALK.
